[57] CLAIM

The ornamental design for a rearview mirror, as shown.

DESCRIPTION

FIG. 1 is a perspective view as seen slightly from the top and one end of the design;
FIG. 2 is a front elevation view thereof;
FIG. 3 is an end elevational view as seen from right to left of FIG. 2;
FIG. 4 is a bottom plan view thereof (the top plan view being a mirror image);
FIG. 5 is a rear elevation view as seen from the side opposite of that shown in FIG. 2; and,
FIG. 6 is an end elevation view of the end opposite that shown in FIG. 3.
